UNITED STATES PATENT OFFICE.

HENRY B. NICHOLS, OF PHILADELPHIA, PENNSYLVANIA.

PORTABLE MELTING AND HEATING APPARATUS.

No. 810,073.

Specification of Letters Patent.

Patented Jan. 16, 1906.

Application filed July 19, 1904. Serial No. 217,282.

To all whom it may concern:

Be it known that I, HENRY B. NICHOLS, of Philadelphia, in the county of Philadelphia and State of Pennsylvania, have invented a new and useful Improvement in Portable Melting and Heating Apparatus, of which the following is a full, clear, and exact description, reference being had to the accompanying drawings, which form a part of this specification.

My invention has relation to portable heating and melting apparatus for use in manufacturing rail-joints of the type described and claimed in Patents Nos. 673,829, 717,025, and Reissue No. 12,074, the object being to provide means of efficient character for supplying the molten spelter or other like material required in the joints, also to provide convenient means for heating the joints preparatory to pouring the spelter therein and for heating the ladles used in such pouring.

With these objects in view I mount one or more melting-pots or crucibles upon a suitable vehicle, said pots or crucibles being each surrounded by a shell or jacket, with an intermediate combustion-chamber in which the heating-burners are situated. These burners are preferably oil-burners, in which the oil is mixed with air in the burners, the air being supplied from storage-reservoirs maintained by an air compressor or compressors also mounted upon the vehicle and driven by a suitable motor. Air from the said reservoirs is also used to force the oil to the burners. Adjacent to the melting-pots or crucibles is a heating-stove for heating the pouring-ladles, the smoke and gases from the combustion-chambers being led through said stove and the heat thereof in part utilized to heat the said ladles. Other burners connected to the air and oil supplying pipes by flexible pipes or hose are also provided for heating the joints. In order to maintain the melting-pots or crucibles in a vertical position notwithstanding the position of the vehicle, the said pots or crucibles are mounted on trunnions in a frame, which is itself hung on trunnions on the vehicle-body, the two sets of trunnions being so arranged that one set will prevent the lateral tilting of the pots, while the other set will prevent tilting in the direction of the length of the vehicle.

My invention also consists in the novel construction, arrangement, and combination of parts, all substantially as hereinafter de-

scribed, and pointed out in the appended claims, reference being had to the accompanying drawings, in which—

Figure 1 is a plan view of apparatus embodying my invention; Fig. 2, a rear view of the same, and Fig. 3 a vertical section through one of the melting-pots or crucibles.

The numeral 1 designates the supporting-vehicle; 2, an air-compressor of any well-known or suitable type, with its attached motor; 3, compressed-air reservoirs or tanks supplied by the compressor 2 through the pipe 4, and 5 an oil-storage tank.

6 designates the outer shells or jackets of the melting-pots or crucibles 7, said shells or jackets having the refractory linings 8 and forming around the pots the combustion-chambers 9.

10 designates suitable covers for the pots. The latter are provided with the trunnions 11, which are journaled in the end bars of a carrier-frame 12, which is in turn supported on the vehicle-frame by trunnions 13, which are at right angles to the trunnions 11.

14 designates the burners in the combustion-chambers 9. Two of these burners are shown in each chamber. These burners are connected to the air-supply pipes 15 by flexible pipe-sections 16 and to the oil-feed pipes 17 by the flexible sections 18. The pipes 15 are supplied from the reservoirs 3 by the pipe 19, and the pipes 17 are connected to the tank 5 by the pipe 20. To furnish pressure for the oil-feed, the pipe 21 from the reservoirs 3 is led into the upper portions of the tank 5.

22 designates the ladle-heating stove, having the burners 22^a supplied by the connections 23 and 24 from the air and oil pipes 15 and 17. Said stove is also heated by the smoke and gases from the combustion-chambers 9, which are carried thereto by the pipes 26. The burners 22^a are used at the commencement of operations to quickly heat the stove 22, after which the requisite heat is largely furnished by the pipes 26. The latter are provided with the ball-joints 27 to take care of the movements necessary to maintain the horizontal positions of the crucibles.

28 designates the burners for heating the joints. These burners are supplied with oil and air by means of the flexible connections 29 to the pipes 15 and 17.

30 designates the tap-holes for the cruci-

bles, which are normally closed by means of plugs of clay or other material. (Not shown.)

31 is a brace connecting the two shells or 5 jackets 6.

The motor or motors for the air-compressor may be electric motors supplied with current by a temporary connection with the supply-conductors of the railway in connection with which the apparatus is being used, or any other suitable power may be used. The vehicle upon which the apparatus is mounted may be drawn by horses or other animals, or it may be propelled after the manner of an automobile by motors of any suitable character.

Various changes may be made in the details of the apparatus without departing from the spirit and scope of my invention. 20 Hence I do not wish to be limited to the precise construction, arrangement, and combination of parts which I have herein shown and described.

Having thus described my invention, what 25 I claim as new, and desire to secure by Letters Patent, is—

1. In apparatus of the character described, the combination with a supporting vehicle, of a frame pivotally supported on said vehicle, a melting-pot or crucible pivotally sup-

ported in said frame, and means for heating said pot or crucible.

2. In apparatus of the character described, the combination with a supporting vehicle, of a frame supported by trunnions on said vehicle, and a melting-pot or crucible supported by trunnions in said frame, the last-named trunnions being arranged at right angles to those of the frame. 35

3. The combination with a supporting vehicle, of one or more melting-pots supported thereon, a ladle-heating stove adjacent to the said pot or pots, and a heat-conducting pipe or pipes leading from the combustion-chambers of said pot or pots to the said stove. 40

4. The combination with a supporting vehicle, of a melting-pot or crucible carried thereby and supported to maintain its vertical position, a ladle-heating stove also carried on the vehicle, and a jointed heat-conducting pipe leading from the combustion-chamber of the pot or crucible to the said stove. 45

In testimony whereof I have affixed my signature in presence of two witnesses.

HENRY B. NICHOLS.
